WHEEL DRESSING DEVICE

Amos P. Steiner, Waynesboro, Pa., assignor to
 Landis Tool Company, Waynesboro, Pa., a corporation of Pennsylvania

Original application December 22, 1928, Serial No.
 327,903. Divided and this application April 20,
 1932, Serial No. 606,470

8 Claims. (Cl. 125—11)

This invention relates to wheel dressing means for a grinding wheel and is particularly designed with a view to its use on a grinding wheel of the character required for grinding both the face and hub of a gear.

A general object is to effect improvements in the construction and means for operating wheel dressing apparatus.

A more specific object is to provide a wheel dressing device which may be moved to dress the grinding wheel without traversing the carriage upon which the work is mounted. This application is a division of my copending application Serial No. 327,903, filed December 22, 1928 for Grinding machines.

Referring to the accompanying drawing, which is made a part hereof and on which similar reference characters indicate similar parts,

Figure 1 is a plan view of the device,

Figure 2, a section on line 2—2 of Figure 1, and

Figure 3, an end elevation of the device.

The wheel dressing device forming the subject matter of this application is designed to be mounted on the work carriage of a grinding machine. As shown a base 10 is suitably secured upon the work carriage of the machine, and a casting 11 is mounted upon and secured to the base 10. The casting 11 has a depending portion 12 which fits in a corresponding socket in the base 10. This permits the casting 11 to be rotated in a horizontal plane to position dressing tools in correct relation with the work. In the casting 11 is provided a cylindrical chamber 13. A piston 14 operates in this chamber, the piston having a piston rod 15 to which is secured a holder 16 which telescopes over a cylinder head or cover 17. A key 18 in the holder fits in a key way 19 in the cover to prevent rotation of the holder.

The holder 16 carries wheel dressing elements 20 and 21 on opposite sides. The piston 14 is operated by pressure fluid controlled by means of a valve shown as a whole at 22. At 23 is an inlet port which port is in communication with a suitable source of fluid under pressure. After passing through the cylinder 13 fluid is exhausted through port 24 to any suitable exhaust line. The valve proper consists of a valve stem 25 having a knurled knob 26 for operating it. The cylinder 13 is provided with ports 27 and 28 through which pressure fluid passes into the cylinder for operating the piston 14. The casting 11 carries a lever or bracket 29 by means of which it is rotated in a horizontal plane.

On the base 10 is a standard 30 through which

is threaded an adjustable stop screw 31, the screw being locked in adjusted position by a nut 32. On the casting 11 is a fixed stop 33 which engages the adjustable stop 31 to stop the casting in correct position to place the dressing tool 5 against the face of the wheel to be dressed.

The operation of the device is as follows: The casting 58 is locked in position by means of a bolt 34 which is operated by means of a handle 35. To dress one face of a grinding wheel the holder 16 10 is moved by pressure fluid to the positions shown in Figure 1 in which position the diamond element 20 is in its forward position and is adjacent the side face of a grinding wheel 36 as shown in Figure 1. When this face of the grinding 15 wheel has been properly dressed the valve stem 25 is manipulated so as to move the piston 14 to the rear. This withdraws the holding element 16 so that it may be swung around until the stop 33 engages the adjustable screw 31 as shown in 20 dotted line position in Figure 1. The valve 25 is again operated to admit pressure fluid to the rear of piston 14 to move it forward to position the diamond 21 in the dotted position shown at 37 where it may engage the surface of the grinding 25 wheel which is at right angles to the surface against which the diamond 20 is positioned as shown in Figure 1. The dressing tool is now in position to dress another face of the grinding 30 wheel which face is at right angles to the one previously dressed.

The movements just described may all be carried out without moving the work carriage. This simplifies operation and insures a more accurate dressing of the grinding surfaces on the grinding 35 wheel.

It will be obvious to those skilled in the art that various changes may be made in my device without departing from the spirit of the invention and therefore I do not limit myself to what is 40 shown in the drawing and described in the specification, but only as indicated by the appended claims.

Having thus fully described my said invention, what I claim as new and desire to secure by Letters Patent, is:

1. A wheel dressing tool of the kind described comprising a bracket, a support for the bracket said bracket being movable in a horizontal plane on the support, means for limiting movement of 50 the bracket within a predetermined range, an element mounted on the bracket and movable in a plane parallel with the plane of movement of the bracket, said element having a pair of wheel dressing tools mounted therein, the tools serving 55

- to dress one face of an abrasive wheel when in one position and another face which is at an angle to the first named face when in another position, both of said faces being dressed from the same pivotal point of rotation of the wheel dressing element, substantially as set forth. 5
2. A tool for dressing the faces of a grinding wheel which faces are at an angle to each other comprising a base, means for securing the base in a fixed position, a bracket mounted upon the base, said bracket being movable in a horizontal plane, means on the base for limiting such movable bracket to an arc corresponding to the angle made by the faces on the wheel, a tool holder mounted on the bracket, hydraulic means for moving said tool holder in the plane of movement of the bracket, a pair of tools mounted in the holder, said tools being swingable to dress the face of an abrasive wheel and a side of the abrasive wheel which is at right angles to the said face, substantially as set forth. 10
3. Means for dressing the cutting surfaces of an abrasive wheel having two surfaces at an angle to each other comprising a tool holder having a pair of wheel dressing tools mounted therein, said holder being pivoted and manually movable about said pivot in a horizontal plane and having hydraulic means for moving it in the same plane but radially of the pivot point to position each of the wheel dressing tools consecutively to dress first one face of the abrasive wheel and then the other, substantially as set forth. 15
4. In a grinding machine of the kind described the combination with a work carriage of a base removably secured on the carriage, a bracket mounted upon the base and movable in a horizontal plane, a holder mounted on the bracket, said holder carrying a pair of wheel dressing tools, said holder being movable axially to position one of the dressing tools in contact with a face of a grinding wheel to be dressed and swingable in a horizontal plane to position the other dressing tool against an adjacent face of the grinding wheel which face is at an angle to the first named face, and adjustable stops for securing the dressing tools in correct position when moved to wheel dressing position, substantially as set forth. 20
5. A wheel truing fixture for angular faced wheels comprising a pivotally mounted tool holder, a tool head slidably mounted in said holder, dressing tools on opposite sides of said head, means to traverse the tool to dress one face of the wheel, means to swing the holder through an angle equal to the angle between the faces to bring the second tool into position to dress the second face, and means to traverse said second tool across said second face, substantially as set forth. 25
6. A wheel truing fixture comprising a base, a support pivotally mounted in said base, a tool head mounted on said support and reciprocable relative thereto, a pair of dressing tools mounted at diametrically opposed points on said head, and adjustable stops on said base portion to determine the angle and position of said angle through which said support will move, substantially as set forth. 30
7. A wheel truing device for dressing a wheel having two faces each at an acute angle to the plane of the wheel comprising a pivotally mounted support, a tool head mounted on said support and reciprocable relative thereto, means on said head to dress said wheel, means to traverse the tool to dress one face of the wheel, and means to swing said support through an angle equal to the angle between the faces to position the head to dress the second face. 35
8. A tool for dressing the faces of a grinding wheel which faces are at an angle to each other comprising a base, means for securing the base in a fixed position, a bracket mounted upon the base, means for moving the bracket in a horizontal plane, means on the bracket for limiting such movement to an arc corresponding to the angle made by the faces on the wheel, a tool holder mounted on the bracket, pressure fluid means for moving said tool holder in the plane of movement of the bracket, a wheel dressing tool mounted in the holder, said holder being swingable to dress a face of the grinding wheel and another face of the wheel which is at an angle to the said first face. 40
